UNITED STATES PATENT OFFICE.

JOHN C. PRY, OF SHELBY, OHIO.

TUBE-ROLLING MILL.

No. 851,435.

Specification of Letters Patent.

Patented April 23, 1907.

Application filed October 2, 1903. Serial No. 175,502.

To all whom it may concern:

Be it known that I, JOHN C. PRY, a citizen of the United States of America, and a resident of Shelby, in the county of Richland 5 and State of Ohio, have invented certain new and useful Improvements in Tube-Rolling Mills, of which the following is a specification.

My invention relates to the manufacture 10 of seamless drawn tubing and is adapted to be used in connection with a tube rolling mill.

The object of my improvement is to provide a means for supporting, guiding and 15 bracing the mandrel rod when the tube or billet is being rolled over the mandrel or plug.

It is well known that in rolling seamless tubing over the mandrel or plug the mandrel 20 is subjected at times to more or less stress or strain, causing it to bend or buckle which will result ordinarily in a defective tube. It is necessary in order to prevent and overcome the strain, to provide a guide that will 25 support and brace the mandrel and keep it in perfect alignment with the grooves in the rolling mill which coincide with the grooves provided in the guide. The groove in the guide is made wider than the corresponding 30 groove in the rolling mill, to permit the mandrel and the tube which is drawn over it to move freely in the guide. In rolling tubes of various sizes it is necessary to support the mandrel at different points of its length to 35 obviate the tendency of buckling or bending as stated. It is important to provide a guide that will permit the tube to move over the mandrel and pass through the guides freely, and at the same time obviate the tendency 40 of the mandrel to buckle or bend when subjected to the stress or strain, to which the mandrel or plug is subjected, which is communicated to the mandrel rod causing it to vibrate and at times lift up, which results in 45 throwing the mandrel rod out of the yoke.

A further object of my invention is to provide a device that will support and guide either long or short rods, making it practical 50 to roll tubes of varying lengths and of different sizes and gages, which considerably reduces the amount of labor that it is now necessary to perform without its use. It will also be noted that the guides are constructed in such a manner as will provide the operator 55 with easy access to the mandrel when it is desired to remove the tube from the mandrel

and pass it through the next groove in the rolling mill, or remove it therefrom when the tube is finished. This is important as it greatly increases the capacity of the rolling 60 mill, as the tubes can be removed from the mandrel with greater facility.

I attain these and other objects by the mechanism illustrated in the accompanying drawing, in which,

Figure 1 is a longitudinal top plan view of my device showing it mounted on longitudinal supports which are attached to the housings of a rolling mill. Fig. 2 is a view in side elevation showing the draw bars attached to 70 a series of angular levers or bolts. Fig. 3 is an end view of one section of my device showing the position of the lever when it is in mesh with the notches provided in the upper portion of the guide, (see Fig. 4). It also 75 shows a side view of the bracket upon which the mandrel guides are mounted. Fig. 4 is a side view of the mandrel guide provided with a hooked portion. This view is taken on the line IV—IV of Fig. 3 and shows the lever in 80 contact with the notched or hooked portion of the guide. Fig. 5 is a side view of the mandrel guide taken through the line III—III of Fig. 3, with the notched or hooked portion removed.

In constructing my device I provide two longitudinal supports 1 and securely attach them to the housings 2 of an ordinary rolling mill. A yoke 3 having suitable apertures provided therein and adapted to adjustably 90 fit the free ends of the supports 1, is provided and adapted to be adjustably mounted on the supports so as to adjust it to conform to the length of the tube it is desired to roll. One end of the mandrel rod 4 is supported in 95 suitable apertures provided in the plate 3^a carried by the yoke 3. The opposite end 4' of the rod 4 has the mandrel plug 7^a attached thereto when the operation of rolling is being performed, and is supported in the groove of 100 the rolling mill which corresponds with the aperture provided in the plate. A series of brackets 5 are adjustably secured to the supports 1 through the medium of the bearings 6. The bearings are shown in Fig. 3 and are 105 made in sections and clamped together by any ordinary clamping means which holds them in frictional contact with the supports 1. This provides a means of adjusting the brackets on the supports to conform to the 110 length of the mandrel rod the operator is using in rolling the tubes. It will be noted

that each bracket can be adjusted independently of the remaining brackets so as to support the mandrel at any point desired. The mandrel guide or support 7 is securely fastened to the bracket 5 by means of bolts *c*. The upper portion of the guide or support is provided with a series of grooves 7' having the lower portions or walls thereof adapted to support the mandrel rod, with the sides forming the groove adapted to guide the mandrel and keep it in alinement with the groove of the rolling mill when it is being subjected to the stress or strain of the rolling operation. The grooves 7' provided in the guides vary in width to provide for the different sizes of mandrel rods, and are made wider than the corresponding grooves in the rolling mill, the purpose of which is to provide a means of permitting the tube to be drawn over the mandrel freely. The tendency of the mandrel rod to vibrate or lift up is obviated as the mandrel is brought in contact with either side of the grooves, and is thereby kept in perfect alinement with the groove provided in the rolling mill. The lower wall 7² of the groove 7' is made convex in form to permit the tube to move over its surface freely when it is being drawn or rolled over the mandrel or plug 7².

30 The form of mandrel guide shown in Fig. 5 is the one I prefer to use, but I have found it desirable in rolling tubes small in diameter or of great length to use the form of the mandrel guide shown in Fig. 4. In using this form of mandrel guide and support a series of levers 8 having one end turned at an angle with the body portion is pivoted to the guides 7 by means of bolts 9. A draw bar 11, having a series of apertures coinciding with the apertures in the turned portions of the levers, is provided and adapted to connect the levers together whereby the levers can be drawn in or out of contact with the notched or hooked portions 10 of the mandrel rod guides simultaneously, permitting the operator to remove the tube from the mandrel preparatory to placing it in the next groove of the rolling mill. When the billet or tube is being rolled over the plug or mandrel 50 tendency of the mandrel rod to vibrate because of the strain that it is being subjected to by the rolling process, is obviated and all danger of buckling or bending removed as the tube is brought in contact with the lower portion of the angular levers and held in place. The dotted lines (see Fig. 1) show the position of the levers when they are out of contact with the notched portions of the mandrel guides. It will be noted that my device can be used successfully with or without the notched or hooked portions of the mandrel guides. My device is designed to be used in conjunction with the ordinary tube rolling mill and is mounted on the frame-work as described.

In performing the function of rolling the tubes the billet is rolled over the plug or mandrel 7² which is secured to one end of the mandrel rod. It will be observed that the plug is made larger in diameter than the mandrel to which it is secured so that the inner periphery of the tube which is being drawn over the mandrel does not fit closely to the mandrel rod, permitting the tubes to be removed from the mandrel when the operation of rolling is completed, readily. In order to provide for the adjustment of the mandrel guides which support the mandrel rod, slots *e* are provided in the brackets 5 through which the bolts *c* pass, affording facilities of raising or lowering the mandrel guide or supports, bringing the lower portion of the groove in contact with the mandrel as desired. When the form of the mandrel guide (shown in Fig. 5) is being used and it is desired to remove the tube from the mandrel rod, the operator pulls the draw bar toward him and it being attached to the angular levers, they are drawn into the position shown by the dotted line E. This leaves the upper portion of the groove 7' without obstruction permitting the mandrel rod to be taken out and the tube removed therefrom.

To briefly state the operation, one end of the billet is inserted in one of the passes between the rolls and forced over the mandrel rods being carried through the guides in alinement therewith, after which the mandrel rod is drawn out through the forward end of the mill.

Slight changes can be made in the form or construction of my device without deviating from the principle involved in my invention. As for instance when it is desired to use the mandrel support or guide, the form shown in Fig. 4 can be used without the hooked portion by providing apertures 12 in the upper portion thereof and using a straight bar. The bracket 5 or bearings shown in Fig. 3 can be made as shown that is to say, by providing each crown of the convexed walls of the guides with countersunk apertures 13 adapted to receive the bolts *c* or other fastening means which register with and are received in apertures formed in the brackets 5, the heads of the bolts constituting the crown of the convex walls, or the brackets may have the guides formed integral therewith.

Having fully described my invention, what I desire to secure by Letters Patent is—

1. A mandrel guide or support for tube rolling mills, composed of a series of mandrel guides or supports mounted on a suitable frame-work and having notches provided in the upper portion thereof, brackets secured to said frame-work, a series of levers pivotally attached to said brackets and adapted to mesh with said notches provided in the upper portion of the mandrel guide.

2. A mandrel guide or support for tube

- rolling mills, having a series of brackets attached to the frame-work, a plurality of mandrel guides securely attached to said brackets, bars pivotally secured to said brackets, whereby the body portion is made to register with a series of notches provided in the upper portion of the mandrel support, a draw-bar having a series of apertures provided therein, whereby the levers are connected together, providing a means of releasing the levers from contact with the notches whereby the tubes can be removed from the mandrel, substantially as and for the purpose set forth.
3. The combination with a suitable support, of a grooved guide mounted thereon, the walls of the grooves being laterally recessed and means receivable in the recesses for closing the upper openends of the grooves.
4. The combination with a suitable support, of a grooved guide block mounted thereon, the walls of the grooves being apertured and a bar removably received in the apertures and extending across the upper ends of the grooves to close the latter.
5. The combination with a suitable support, of a grooved guide block mounted thereon, the walls of the grooves being apertured, a bar pivotally supported intermediate its ends on the block and receivable in the apertures and means connected to one end of the bar for moving it into or out of the apertures.
6. The combination with a frame, rolls having passes therein, and mandrel rods supported in an abutment on the frame, of a plurality of open guides in alinement with the passes adapted to support the entire piece being operated upon, and adapted to permit the said piece being removed laterally from the guides.
7. The combination with a frame, rolls having passes therein and mandrel rods supported in an abutment at one end of the frame, of a plurality of open guides adapted to support the mandrels at intervals throughout their length and which admit of the tubes formed being removed laterally from the guides.
8. The combination with a frame, rolls and mandrel rods, of guides in alinement with the passes of the rolls, the height of each guide being greater than the distance from the bottom of its pass to the horizontal plane of the widest portion of the pass, the guide being constructed and arranged to admit of transverse movement of the piece being operated upon from its position in the guides.

Signed at Mansfield, O. this 25 day of Sep't, 1903.

JOHN C. PRY.
